United States Patent Office.

J. WALL WILSON, OF NEW YORK, N. Y.

Letters Patent No. 99,509, dated February 1, 1870.

IMPROVED CAR-BRAKE AND STARTER.

The Schedule referred to in these Letters Patent and making part of the same.

To all whom it may concern:

Be it known that I, J. WALL WILSON, of the city, county, and State of New York, have invented a new and useful Improvement in Car-Brakes and Starters, of which the following is a full, clear, and exact description, reference being had to the accompanying drawing, forming part of this specification, and in which—

Figure 1 represents a plan of the running portion of a horse-railroad car, with my improved brake and starter applied thereto.

Figure 2, a mainly central longitudinal section of the same.

Figure 3, a side view, from the exterior, of a detached portion, showing a clog or shoe of one of the brakes, with devices for operating the same, and

Figure 4, an inside view thereof, on an enlarged scale.

Similar letters of reference indicate corresponding parts.

My improvement is applicable to horse-railroad cars, and other vehicles; and

The invention consists in a novel and advantageous combination of mechanism, whereby the same motion that is used to put on the brakes, serves to actuate or generate a power for starting the car after the brakes are released, or the brakes may be operated at pleasure, without actuating the starting-means, and the invention includes a new and useful combination of devices, including eccentrics to the clogs or shoes of the brakes, for operating the same.

Referring to the accompanying drawing—

A represents the frame, which carries the running gear of the car, and

B B', its front and rear wheels, to which X X' are the axles.

These wheels are provided, on their inner side or face, with supplementary peripheries, C C', and circular racks or ratchet-wheels, D D', both of lesser diameter than the wheels B B', so as not to come in contact with the ground.

The brake or brakes are made up, in part, of clogs or shoes E E', and suitably-clothed or formed friction-wheels F F', the latter being designed to be operated when it is required to generate a power for starting the car after the brake-force or pressure has been removed, while the clogs or shoes E E' are used altogether, or more exclusively, when, in putting on the brake-force, as in going down-hill, it is not required to accumulate a power for starting the car again. Both of these brake-means are or may be operated by one and the same primary device, at either or opposite ends of the car, and which may be an ordinary brake-shaft or rod, G or G', provided with a crank or handle, a or a', and the arrangement here shown is such, as that on turning either of said shafts in the one direction, the fric-

tion-wheels F F', and the brake-shoes E E', are thrown into working-contact with the peripheries C C' of the wheels B B', and on turning such shaft or shafts G or G' in the reverse direction, beyond the point or extent necessary to release the friction-wheels F or F' from working-contact, the clogs or shoes E E' are alone brought to bear upon the treads of the wheels B B'. To accomplish this twofold brake-action, I adopt the following combination and arrangement of parts:

The shoes E E' are pivoted, as at b b', to the main frame A, and each opposite pair thereof carries loose upper and lower cross-shafts, H I or H' I', extended or arranged so as to connect them.

The lower ones, I I', of these shafts, have the friction-wheels F F' loosely hung, so as to rotate upon them, and said friction-wheels are provided with pulleys or small barrels, c c', made fast to them on their inner sides.

The upper shafts H H' also have, loosely arranged upon them, directly over the barrels c c', small pulleys, d d'.

J J' are intermediate cross-shafts, turning, at their ends, in bearings made fast to the main frame, and having small barrels e e' f, and e' e' f, fast on them.

Chains g h and g' h' are made fast at their one end, and wound in reverse directions around barrels i i', at the lower ends of the operating-shafts G G', or it may be a single chain to each of said shafts, wound in reverse directions around its barrel i or i', so as virtually to form two chains.

The opposite ends of these chains, g h and g' h', are made fast, the ones, g g', to the barrels f f', and the others, h h', to (either directly, or through rods k k') opposite arms of a lever or beam, K, pivoted, as at j, to a brace extending across the main frame, which beam is connected, by rods l l', to the radial pins or projections m m' on the shafts I I'.

The barrels e e' and e' e' have secured to them, chains u u', which chains are extended and lapped around the barrels c c' of the loose friction-wheels, and from thence passed up over the loose pulleys d d', and made fast, respectively, to sliding bars L L', carrying, at their one end, pawls o o', which gear, when drawn up over them, with the ratchet-wheels D D'.

These sliding bars L L' are made fast, at their other ends, to springs M M'.

N N' are springs, which serve to draw back the brakes when released, said springs being arranged to pull on the brakes through their lower connecting-shafts I I'.

When applying the clogs or shoes E E' to the wheels, they are not only drawn against the wheels B B' by the pull of either chain h h', (according to the end of the car from which the brakes are being worked,) and rods k k' and l l', through the action of the beam or

lever K, on suitably turning either operating-shaft G or G', to wind the chain h or h' upon its barrel, but the rods l l', in pulling on the shoes E E' through the shafts I I', also turn said shafts, which have their end-bearings, by eccentrics P P', within the shoes, so that said eccentrics, being turned together with the shafts I I', bring up, in a gradual and powerful manner, the shoes E E' against the wheels B B'. This action of the eccentrics P P' on the shoes, in addition to the direct swinging action or pull on them, through the radial connection of the rods l l', or other suitable means, with the shafts I I' carried through the eccentrics by the shoes, is an important feature in the operation of the brakes.

In thus applying the brake-power through the shoes E E', and which may be done in going down-hill, or when it is not necessary to accumulate a power for starting the car again, the friction-wheels F F' are not brought up to act as brakes against or on the wheels B B', inasmuch as in turning the shafts G or G', to apply the shoes E E' to the wheels, the chains o' g' are slackened, and the shafts J J' consequently not turned, which causes no pull to be made on the chains u or u'. But on turning the shafts G or G' in a reverse direction, and to an extent beyond that which is necessary to merely release the shoes E E' from frictional contact with the wheels B B', then the chains h or h' are slackened, and the chains g or g' tightened or pulled upon, so as to turn the shafts J or J', and cause pull on the chains u or u', which draws the friction-wheels F or F' up against the wheels B B', to make them act against the periphery C or C', to accumulate a starting-power, whilst the shoes E or E' act as brakes, but not turning the shafts I or I', to operate the eccentrics P P', by reason of the barrels e or e' and their wheels f or f' being loose on the swinging shafts I or I'. On the friction-wheels F or F' being thus brought up against said peripheries C or C', in being rotated by

the wheels B or B', their barrels or pulleys e or e' work the chains u or u' by the coiled lap of the same around said barrels, so as to pull on the sliding bars L or L' against the action of the springs M or M', and cause their pawls o or o' to be drawn up over and into gear with the ratchet-wheels D or D'. This causes a power to be generated or accumulated for starting the car again, inasmuch as on releasing hold of the shafts G or G', the distended springs M or M' are free to fly back and through the sliding bars L or L', and their pawls o or o' pull on the ratchet-wheels D or D' to turn the wheels B or B' so as to make them act as drivers to the car.

The strength of the starting-power will be determined by the amount of distension given to the springs M or M' and forward feed or throw of the pawls o or o', over the wheels D or D', which, of course, is regulated by the amount of brake-force, as applied by the brakeman, or length of time the wheels F or F' are held in contact with the wheels B or B', and the speed of the latter at the time.

What is here claimed, and desired to be secured by Letters Patent, is—

1. The arrangement of the eccentrics P or P' in the body of the swinging shoes E or E', and fast on their shafts I or I', which carry operating radial pins m or m', for operation, substantially as specified.

2. The combination, with the brake-shoes E E', of the friction-wheels or brakes F F', the ratchet-wheels or racks D D', the starting-springs M M', together with their pawls, and the chains, rods, and mechanism by which the shoes E E' or the friction-wheels F F' may be operated at pleasure, as required, essentially as herein set forth.

J. WALL WILSON,
